Primary Examiner — Jack Reickel*Assistant Examiner* — Michael A Kervin(74) *Attorney, Agent, or Firm* — Dority & Manning, P.A.(57) **CLAIM**

The ornamental design for a mounting track, as shown and described.

DESCRIPTION

FIG. 1 is a front perspective view of the mounting track; FIG. 2 is a rear perspective view of the mounting track of FIG. 1;

FIG. 3 is a left side view of the mounting track of FIG. 1; FIG. 4 is a right side view of the mounting track of FIG. 1; FIG. 5 is an overhead view of the mounting track of FIG. 1; and,

FIG. 6 is a bottom view of the mounting track of FIG. 1. The broken lines shown in the Figures represent portions of the mounting track that form no part of the claimed design.

1 Claim, 3 Drawing Sheets(56)
